UNITED STATES PATENT OFFICE

2,330,874

SPIKE EXTRACTOR

Carson Dewey Eaves, Memphis, Tenn.

Application August 12, 1941, Serial No. 406,543

2 Claims. (Cl. 254—18)

The present invention relates to a pulling apparatus and more particularly to a jack assembly for extracting spikes, nails, bolts and the like from railroad ties and planks.

The primary object of this invention is to provide a compact, jack operated, portable spike puller or extractor, wherein the spike engaging member follows the movement of the movable jack piece during the operation of said jack.

Another object is to provide a spike extractor adapted to pull spikes of varying lengths and sizes, either with or without head portions.

The broad concept of this invention embraces a pulling apparatus comprising a jack assembly wherein the movable jack piece has associated therewith a spike engaging member which follows the movement of said jack piece during the operation of the jack, and additionally a plurality of auxiliary members for detachable engagement with said jack piece for extracting spikes of varying lengths and shapes from places which are difficult of access.

Other and further objects and advantages of this invention will be apparent from the following description thereof and from the claims appended thereto.

In the drawings, wherein like numerals refer to like or corresponding parts throughout the several views.

Figure 1 is a side elevation of the spike extracting apparatus and embodies the principal features of this invention.

Figure 2 is a front elevation of the apparatus depicted in Figure 1.

Figure 3 is a view taken along the lines 3—3 of Figure 1, in the direction indicated by the arrows.

Figure 4 is a side elevation of a modified form of the invention wherein the spike engaging member is adapted for engagement with a spike disposed below the level of the jack base.

Figure 5 is a front elevation of the spike engaging member first depicted in Figure 4.

Figure 6 is a side elevation of still a further modification showing the position of the spike engaging member where the spike being extracted is relatively long.

Figure 7 is a side elevation of another modified form of the invention showing the extraction of a headless spike disposed below the surface level of the jack base.

Figure 8 is a longitudinal vertical section of the spike receiving member first shown in Figure 7.

Figure 9 is a bottom plan view of the spike receiving member of Figure 8, and

Figure 10 is a detail, partly in section, of the spike extracting member laterally extending from the lower end portion of the movable jack member.

Referring now to the drawings, and more particularly to Figures 1, 2 and 3 thereof, the numeral 10 generally indicates a jack, said jack having a housing 11, a handle 12, a base portion 13 and a movable jack piece 14.

The present invention does not reside in the structure of the jack 10 relative to the various engaging parts which cooperate to provide upward movement of the jack piece 14 when the handle 12 is pumped. Any suitable jack known to the art will be adaptable in the practice of this invention.

A C-shaped collar 15 extends laterally from the lower end portion of the jack piece 14 and is adapted for movement therewith. The said collar 15 is interiorly recessed to receive the head portion 16 of the spike 17 to hold the same against lateral slippage.

The upper portion of the jack piece 14 carries a head 18 which may be of any suitable configuration. A bolt or spike head engaging cap 19 is internally recessed to fit snugly over the head 18 and is held against lateral slippage. The cap 19 is provided with a laterally extending C-shaped arm 20 which is recessed to receive the head of a bolt, the center point of the recessed portion being along the vertical axis extending upwardly from the center point of the recessed portion of collar 15.

The cap 19 is removable from the head 18 and only plays a part in the spike pulling operation where very long spikes are being extracted, as described hereinafter.

In the operation of this form of the invention, the spike 17 is first extracted or pulled from the plank in which it is embedded to such a distance as to enable the head 16 thereof to be slipped into the recessed portion of the collar 15. The jack handle is then pumped and the spike 17 is withdrawn from the plank by a series of movements corresponding to the upward movement of the jack piece 14 within the housing 11.

Referring now to Figures 4 and 5, there is shown a modified form of this invention wherein an auxiliary bolt or spike engaging member is provided and is generally indicated by the numeral 21. The spike engaging member 21 has a shank 22 having mounted thereon in spaced apart relation a plurality of portions, indicated as 23 and 24, which preferably have the same general

size and configuration as the head of the spike being extracted.

The member 21 is provided with a bifurcated arm 25 at the lower end thereof, said arm having a bolt head receiving ring 26. The arm 25 is apertured to receive the bolt 27. A nut 28 threadedly engages said bolt 27 to furnish means for increasing or decreasing the diameter of ring 26.

The spike engaging member 21 is primarily used in combination with the jack assembly where the spike to be extracted is below the surface level upon which the base 13 of the jack is disposed. One of the portions, such as 24, mounted along the shank 22 is positioned in the recessed portion of the collar 15. The member 21 is then adapted to move upwardly with the collar 15.

In the operation of this form of the invention, the spike 30 is first pulled out of the plank in which it is embedded to such an extent that the head 29 can be slid into the ring 26. The handle 12 of the jack 10 is pumped and the jack piece 14, the collar 15 and the member 21, move upwardly in a series of moves.

Referring now to Figure 6, there is shown the apparatus for extracting long bolts or spikes, such as 31, provided with a head 32.

The bolt 32 is first partially extracted, using the apparatus illustrated in Figures 1, 2 and 3. The ring 26 of member 21 engages head 32 of bolt 31, while the collar 24 is engaged in the recessed portion of the arm 20 of the cap 19 which is secured on the head 18 of the jack piece 14. Pumping of the handle 12 will elevate the jack piece 14, the member 21 and extract the bolt 31 from the planks in which it is embedded.

In the extraction or pulling of very long bolts or spikes the apparatus of Figures 1, 2 and 3 is first used to partially pull the bolt or spike upwardly. Thereafter the head of the bolt or spike is engaged in the recessed portion of the arm 20 for the further operation of the jack.

Referring now to Figures 7, 8 and 9, there is shown a jack attachment, generally indicated as 33, in combination with the complete jack assembly, for use in pulling headless spikes, nails, pipes or the like.

The attachment 33 is internally recessed and is provided with a cut away side portion, indicated as 34, and a bottom slot 35 which is of such size so as to permit the insertion of the headless spike 36 therethrough to bear against an internal projecting portion 37, and to prevent substantial lateral slippage.

A wedge 38 having a serrated side portion 39 is provided for insertion through the opening 34, the serrated portion 39 abutting the headless spike 36 as it bears against the shoulder 37, to firmly hold said spike 36 in said attachment 33.

A bolt 40 is mounted in the upper end portion of the attachment 33 and carries a head 41 adapted to engage in the recessed portion of the collar 15. Bolt 40 is adapted to fit in ring 26 of the elongated spike engaging member 21 when extracting headless spikes disposed substantially below the base 13 of the jack 10.

In the operation of this form of the invention the spike 36 is first extracted from the plank to such a degree that it can be inserted through the slot 35 of the attachment 33. The wedge 38 is inserted through the opening 34 with the serrated portion 39 thereof abutting the spike 36. A tight fit is accomplished by hammering wedge 38 to urge spike 36 sideways in said slot 35. In this position of the wedge 38, the top end of the spike 36 partially bears against the shoulder 37a.

The head 41 of the bolt 40 is slid into the recessed portion of the collar 15. Pumping of the handle 12 of the jack 10 elevates the jack piece 14 to withdraw the spike 36 by a series of moves.

The Figure 10 shows the collar 15 secured to the lower end portion of the jack piece 14, as by bolts 42. The collar 15 may be cast in one piece with the jack piece 14, if so desired.

It is to be understood that various modifications of this invention will be apparent to those skilled in the art without departing from the spirit thereof, and it is therefore desired to be limited only by the scope of the appended claims.

Having thus described my invention, I claim:

1. A spike extractor comprising a jack assembly including a vertically movable jack piece, a laterally extending recessed C-shaped member carried by the lower end portion of said jack piece, a second laterally extending recessed C-shaped member removably carried by the upper end portion of said jack piece, the recesses in each of said C-shaped members being substantially in vertical alignment, an elongated arm having a bifurcated spike engaging portion, and said arm being provided with a plurality of spaced-apart collars each adapted for selective engagement in the said recessed C-shaped members.

2. A spike extractor comprising a jack assembly including a vertically movable jack piece, a recessed member carried by said jack piece, a second recessed member carried by said jack piece in spaced relation to said first mentioned recessed member, the recesses in each of said members being substantially in vertical alignment, an elongated arm having a spike engaging portion, and said arm being provided with a plurality of spaced apart collars each adapted for selective engagement in the said recessed members.

CARSON DEWEY EAVES.
